APPARATUS FOR TREATING LIQUID WITH A GAS

Application filed July 15, 1930. Serial No. 468,015.

My invention relates to improvements in apparatus for treating liquid with a gas and more particularly to an improved apparatus for the concentration of ores by what is commonly known as the flotation process, in which the ores or other substances are subjected to aeration in an aqueous separating medium in the presence of suitable agents for the formation of a froth containing valuable portions of said ores or other substances, and thereby separating said values from the barren or rocky constituents thereof.

More particularly the present invention relates to an improved means for regulating and controlling the air introduced into flotation machines of the cascade type.

The principle of operation and novel features of the invention will be understood from the following description, taken in conjunction with the accompanying drawings, in which similar reference characters refer to similar parts throughout the several views.

Fig. 1 is a longitudinal sectional elevation in exaggerated proportion of the flotation cell taken on line 1—1 of Fig. 2.

Fig. 2 is a transverse section of the flotation cell taken on line 2—2 of Fig. 1.

Fig. 3 is a section in detail of the air inlet means.

Fig. 4 is a fragmentary section on line 4—4 of Fig. 3.

Fig. 5 is a fragmentary section on line 5—5 of Fig. 3.

The drawings illustrate one type of cascade flotation machine equipped with the improved means for regulating and controlling the introduction of air, embodying my invention. Air under pressure enters the machine through the headers 10, and passes through the primary air slots 12. These primary air slots 12 outlet into a central air chamber 14 running the entire length of the cell. The cross sectional area of these primary air slots is such that they have capacity for carrying several times the total quantity of air required for the operation of the machine, thereby insuring that sufficient air is always being supplied to the central air chamber to minimize any local fluctuations in air

pressure occasioned by varying the size of the discharge openings to be presently described outletting from such chamber to the pulp body. Openings 16, of suitable size and at suitable intervals, are provided at the top of the air chamber 14. After passing through these openings 16 the air finally exits between the flexible rubber strips 20 into the apparatus at the base of the air-lift chamber 18. The sliding valves 22 are also provided with openings 16a. These valves 22 are seated in position against the inside of the top of the air chamber 14 by means of springs 24, which are secured to the cell bottom at 26. These springs 24 have the effect of providing a flexible base on which the sliding valves 22 slide and at the same time prevent an accumulation of dirt under them and keep the valves 22 snugly seated against the openings 16 in the top of the air chamber 14.

Along each side of the air chamber 14 are secured the strips of pure gum rubber 20 which come together at the top, as shown at 28. While the machine is operating, these rubber strips 20 are held apart by the air pressure and the air outlets between them in the form of a substantially continuous sheet. When the air is shut off these strips come together, making a seal which prevents the pulp from entering the air chamber. The valves 22 which require only a slight movement to open or close the openings 16, are operated by rods 30 attached to the ends of the valves.

The rods 30 pass through stuffing boxes 32 to prevent escape of air and are provided with threads and threaded hand wheels 34 by which means the valves 22 may be conveniently moved horizontally to open or close or adjust the size of the openings 16 with extreme nicety.

The fragmentary section Fig. 4 shows the valves 22 in three different positions. At 44, the openings 16 are entirely open to the passage of air. At 46, they are half closed and at 48, they are entirely closed.

Partitions 36 are introduced at intervals in the primary air slots 12 in order to prevent collapse of the slots and are staggered as shown in Fig. 5.

In the operation of cells of great length,

now in current use, it is important to have 5 separate control of the air volume in different parts of the cell. For example, in a rougher cell 100 feet long, it is desirable to use a smaller quantity of air in the first third of the cell where a high grade concentrate is required and a larger quantity of air in the rest of the cell where it is important to make clean tailings regardless of the grade of the

10 concentrate. In Fig. 1 is shown a longitudinal section of a flotation cell in which the concentrate is removed separately from three compartments of the cell, as indicated by the concentric launders 38 and discharge spouts

15 40. In order to regulate the volume of air to these three compartments, it is necessary only to regulate the air to the two end compartments by means of the hand wheels 34 after getting the proper amount of air through the 20 center compartment by regulating the main valve to the apparatus, as indicated at 42.

I have found that the regulation of the volume of air entering the flotation cell by the accurate control of the size of the openings 25 through which the air exits directly or substantially directly into the pulp, results in a steadier flow of air and a better distribution of air in the flotation cell than is the case where the volume of air to the cell is regulated 30 by valves placed at some distance from the exit openings into the cell.

I have also found that uniform distribution 35 of air in the flotation cell is facilitated by providing means for leading air to the zone immediately in front of such openings in substantially greater volume than it can be discharged through such openings and so insuring a constant head of air from the primary 40 source of air under pressure which the pressures locally prevailing will not fluctuate widely with changes in the size of such air exit openings.

While the present invention has been described with particular reference to a flotation 45 cell operating on the cascade principle, it will be understood that it is capable of application to other types of cells in which uplift action is to be produced. It will be further understood that various changes in the 50 details of the construction may be made without departing from the invention, which is not to be deemed as limited other than as indicated in the appended claims.

I claim:

55 1. In an ore flotation apparatus, an elongated tank adapted to contain ore pulp, a longitudinally-extending uplift chamber within said tank, an air chamber disposed beneath the lower end of said uplift chamber and substantially coterminous as to length with said uplift chamber, means disposed on the upper side of said air chamber for defining a substantially continuous slot through which to inject air in an upward direction into pulp contained within said

tank, thereby producing an upward circulation of pulp through said uplift chamber, said means being responsive to changes in the pressure at which air is supplied to said air chamber for opening and closing said slot, and valve means immediately adjacent to and beneath said slot-forming means for controlling the volume of air supplied through said slot.

2. In an ore flotation apparatus, an elongated tank adapted to contain ore pulp, a longitudinally-extending uplift chamber within said tank, an air chamber disposed beneath the lower end of said uplift chamber and substantially coterminous as to length with said uplift chamber, said air chamber being provided on its upper side with a series of closely spaced openings, a valve member mounted in said air chamber for controlling flow of air through said openings, and means disposed immediately adjacent to and above said openings for defining a substantially continuous slot through which to inject air as a substantially continuous sheet in an upward direction into pulp contained within said tank, thereby producing an upward circulation of pulp through said uplift chamber, said slot-forming means being responsive to changes in the pressure at which air is supplied through said openings for opening and closing said slot.

3. In an apparatus for treating liquid with a gas, a tank adapted to contain liquid, a gas-receiving chamber disposed adjacent the lower end of said tank and substantially coterminous as to length with a linear dimension of said tank, means disposed on the upper side of said gas-receiving chamber for defining a substantially continuous slot through which to inject gas in an upward direction into liquid contained within said tank, said means being responsive to changes in the pressure at which gas is supplied to said gas-receiving chamber for opening and closing said slot, and valve means immediately adjacent to and beneath said slot-forming means for controlling the volume of gas supplied through said slot.

4. In an apparatus for treating liquid with a gas, a tank adapted to contain liquid, gas distributing means comprising a gas-receiving chamber associated with said tank, said gas-receiving chamber being provided with a series of closely spaced openings for discharging gas into said liquid, a valve member mounted adjacent said openings and substantially coterminous as to length with said series of openings for simultaneously adjusting the effective size of all of the openings in said series, and means disposed immediately adjacent to said valve member and said openings for defining a substantially continuous slot through which to inject gas as a substantially continuous sheet into liquid contained within said tank, said slot-form-

ing means being responsive to changes in the pressure at which gas is supplied through said openings for opening and closing said slot.

5 In testimony whereof, I have signed my name to this specification this 7th day of July, 1930.
